United States Patent Office.

JOSEPH C. COULT, OF SAN FRANCISCO, CALIFORNIA.

Letters Patent No. 77,592, dated May 5, 1868.

IMPROVEMENT IN FURNACES AND CONDENSERS FOR COLLECTING QUICKSILVER.

The Schedule referred to in these Letters Patent and making part of the same.

TO ALL TO WHOM IT MAY CONCERN:

Be it known that I, JOSEPH C. COULT, of the city and county of San Francisco, and State of California, have invented certain new and useful Improvements in the Mode of Constructing my Furnace and Condensers, for which two Letters Patent of the United States have been granted to me, for the reduction of quicksilver and other ores, and volatile substances, concentrating the volatile substances in the condensing-chambers by amalgamation; and I do hereby declare that the following is a full description of my improved invention, reference being had to the accompanying drawings, and to the letters of reference marked thereon, the annexed drawings making a part of this specification.

Figure 1 represents the frame of the furnace, which is constructed as in the drawings represented.

B B, the two fire-chambers; C C, the two ore-chambers; D, the vapor-chamber. I use, instead of the water-linings *ff*, or in connection therewith, which divide the compartments of the furnace, the gratings *d d*, shown at fig. 1 and Figure 3, to divide the compartments through which the fire passes, from the chambers B B, into and through the cross-section of the ore in the chambers C C, and out into the vapor-chamber D.

Underneath, and attached to the vapor-chamber, is the vapor-pipe C, which is connected to the condensing-chambers H H H, all of which is made of or lined on the inside with plates of copper, silver, or any other material that can be coated with quicksilver. I also place in the space or opening of the condensing-chamber, through which the fumes pass, a series of punched copper, silver, or plate, made of any other material that will or can be coated with quicksilver, *a a a a*, placed one above the other, leaving a space between the plates, to let the fumes circulate, in such a manner that when the fumes pass through the holes in the plate, Figure 4, below, they must come in contact with the rolled part of the plate above, (see dotted lines *a' a' a' a'*, also fig. 4.) All the plates on the inside of the condenser being first coated with quicksilver, readily take up and amalgamate all the fine vapors of quicksilver that would otherwise pass through and probably be lost, all substantially as described and for the purposes set forth.

What I claim as new, and desire to secure by Letters Patent, is—

1. The arrangement of the panes *d' d' d'* in the ore-chambers C C, instead of the vapor-chamber D.
2. The arrangement of the grating *d d*, placed on the inside of the ore-chambers C C, to be used with or without the water-linings *ff*, as may be desired, as and for the purposes set forth.
3. The arrangement of making or lining the inside of the condensing-opening or pipes H H H, with copper, silver, or other material that can be coated with quicksilver, as and for the purposes set forth.
4. The arrangement of placing in any part of the condensing-openings H H H, leading from the furnace to the final escape into the open air, a series of punched copper, silver, or plate, made of other material, that will or can be coated with quicksilver, for the purpose of amalgamating the fumes of mercury thereto, and saving all that would otherwise escape, as and for the purposes set forth.

San Francisco, December 4, 1867.

JOSEPH C. COULT.
